UNITED STATES PATENT OFFICE.

MAX F. MADIER AND NATHAN MILENKO, OF NEW YORK, N. Y.

DESIGN FOR A RING.

Application filed November 30, 1925. Serial No. 15,591. Term of patent 7 years.

To all whom it may concern:

Be it known that MAX F. MADIER and NATHAN MILENKO, citizens of United States, residing at New York, in the county of New York and State of New York, have invented a new, original, and ornamental Design for Rings, of which the following is a specification, reference being had to the accompanying drawing, forming a part thereof.

We claim:

The ornamental design for a ring, as shown.

MAX F. MADIER.
NATHAN MILENKO.
